US00D831460S

(12) **United States Design Patent** (10) **Patent No.:** **US D831,460 S**
Abbott et al. (45) **Date of Patent:** **** Oct. 23, 2018**

(54) **AXE**

(71) Applicant: **The Ames Companies, Inc.**, Camp Hill, PA (US)
(72) Inventors: **Aaron Abbott**, Harrisburg, PA (US); **Jared Aller**, Oakland, CA (US); **Beau Oyler**, Walnut Creek, CA (US); **Yulian Bagirov**, Oakland, CA (US); **Charles Bates**, Oakland, CA (US)

(73) Assignee: **The Ames Companies, Inc.**, Camp Hill, PA (US)

(**) Term: **14 Years**

(21) Appl. No.: **29/496,674**

(22) Filed: **Jul. 16, 2014**

(51) LOC (11) Cl. **08-02**
(52) U.S. Cl. **USPC** **D8/76**

(58) **Field of Classification Search**

USPC .... D8/10, 14, 31-32, 44-47, 61, 68, 75-81, D8/97, 99, 107; D22/117, 118; 30/308.1, 308.3; 7/145; 254/26 R; 81/19-26, 489-490
CPC A01B 1/20; A62B 3/005; B26B 23/00; B25D 1/00; B25F 1/00; B25F 1/006; B25F 1/02; B25G 1/04; B25G 3/28

(74) Attorney, Agent, or Firm — Brooks Kushman P.C.

(57) **CLAIM**

The ornamental design for an axe, as shown and described.

DESCRIPTION

FIG. 1 is a top view of the axe;
FIG. 2 is a bottom view of the axe;
FIG. 3 is a back view of the axe;
FIG. 4 is a front view of the axe;
FIG. 5 is a left view of the axe; and,
FIG. 6 is a right view of the axe.

The broken lines in the drawings depict environmental subject matter only and form no part of the claimed design.

1 Claim, 3 Drawing Sheets
